RANGE CONSTRUCTION

Samuel Klute, South Bend, Ind.

Application February 28, 1938, Serial No. 192,980

8 Claims. (Cl. 126—1)

This invention relates to improvements in range constructions, and particularly to cooking ranges using wood, coal or like fuel.

Certain disadvantages result in the application of enamel or like finishing material to range castings, and it is, therefore, the primary object of this invention to provide a novel range construction utilizing enameled sheet metal parts for the range exterior.

10 A further object is to provide novel means for mounting preformed enameled panels on the exterior of a range.

15 A further object is to provide a range construction having exterior enameled sheet metal panels which are protected from the influence of high degrees of heat by an air circulation arrangement.

20 A further object is to provide a range construction wherein air intake openings and dampers therefor are completely concealed.

25 A further object is to provide a range construction wherein functional parts are substantially concealed by the use of sheet metal exterior panels to enhance the ornamental appearance thereof.

Other objects will be apparent from the description and appended claims.

In the drawings:

30 Fig. 1 is a front perspective view of the range. Fig. 2 is a fragmentary vertical sectional view taken on line 2—2 of Fig. 1.

Fig. 3 is an interior perspective view of an exterior end panel of the range.

35 Fig. 4 is a sectional view taken along line 4—4 of Fig. 3 and illustrating the application of the exterior end panel to the range body.

Fig. 5 is a fragmentary detail sectional view taken on line 5—5 of Fig. 4 and illustrating the mounting of the exterior end panel to the range body.

40 Fig. 6 is a fragmentary interior perspective view of an exterior panel mounted at the front of the range body.

Fig. 7 is a fragmentary vertical sectional view taken on line 7—7 of Fig. 6 and illustrating the mounting of the panel on the front of the range body.

Referring to the drawings which illustrate the preferred embodiment of the invention, the numeral 10 designates the top of the range which is mounted on a range body comprising a front 11, ends 12, back 13 and bottom 14. An oven compartment 15 is fixedly mounted in the range body between the top and bottom thereof and preferably centrally of the ends, said oven being

accessible by means of an oven door 16. The range front is provided with the conventional access opening (not shown) for removal of soot, etc., in the portion thereof below the oven, and is concealed by a panel 17. Compartments at the ends of the range body constituting respectively a combustion chamber and a warming or reservoir chamber are closed by doors 18 at the range front. The range body is mounted on a base comprising legs 19 and rails 20. A 10 splash plate or upper back plate 21 projects above the range body at the rear thereof. A suitable partition 22 extends between the bottom of oven 15 and the range bottom 14 adjacent to and defining the combustion chamber. 15

Within the combustion chamber and intermediate the height thereof is mounted a frame 25 in which grates 26 are journaled. Frame 25 supports fire pot 27 which tapers upwardly and outwardly from said frame and is provided with 20 a plurality of apertures 28 adjacent its upper end. The upper margin of the fire pot 27 preferably bears against the walls of the combustion chamber. The end wall 12 of the range body at the combustion chamber is provided with an open 25 ing 29 therein adjacent fire pot 27, and a damper 30 is adjustably mounted to control said opening. An opening 31 is formed in end wall 12 below opening 29. An opening 32 is formed in the range bottom 14 adjacent opening 31. An 30 inclined plate 33 extends between range bottom 14 and end 12 to close the combustion chamber from openings 31 and 32. An ash receptacle 34 is removably mounted on bottom 10 below frame 25 in the combustion chamber. A feed pouch 35 is carried by end wall 12 above fire pot 27 to project outwardly thereof and terminate inwardly of the ends of the range top 10.

A sheet metal panel 36, best illustrated in Figs. 3 and 4 is mounted at the end of the range body. 40 Panel 36 is cut away at 37 at its upper end, whereby feed pouch 35 may extend therethrough. Panel 36 is provided with perpendicular flanges 38 at its vertical and bottom edges to space the panel from end wall 12, and at its upper edge and on opposite sides of cut away 45 37 is provided a perpendicular flange 39 of less width than flanges 38. Integrally formed with front vertical flange 38 are a pair of inturned ears 40 extending substantially 50 parallel to panel 36, and an opening 41 is formed in part in said ear 40 and in part in said flange 38. Edge cut-outs 42 are formed in front vertical flange 38 to accommodate hinge members (not shown) for the adjacent door 18. In the 55

rear vertical flange 38 are provided apertures 43. A pair of small plates 44 are fixedly secured to the range body in horizontal position at the front edge of the end wall 12, and these plates 5 are angularly outwardly bent at 45 adjacent their rear end portions. The panel 36 is positioned at the exterior of end wall 12 with ears 40 bearing against said wall, whereby apertures 41 fit over plates 44, and the angularly bent lips 45 of said 10 plates 44 overlie said ears 40 rearwardly of said apertures 41. The parts are so proportioned that the front flange 38 lies substantially flush with range front 11 when ears 40 are operatively locked behind lips 45 of plates 44. Suitable stove 15 bolts 46 extending through apertures 43 and apertures in the seam at the rear vertical corner of the range body, serve to secure the panel 36 to place. It will be seen that this construction 20 substantially seals the vertical and bottom edges 20 of the panel by abutment thereof against the range body, while space is provided at the top of the panel between the end wall 12 of the range body and the edges of flange 39. The panel preferably terminates in spaced relation 25 below stove top 10.

It will be observed that the panel 36 provides an air passage outwardly of end wall 12. Thus air which passes upwardly through opening 32 in bottom 14 and through opening 31 in wall 12 30 passes inwardly of panel 36 as indicated by the arrows. A portion of this air flow, as governed by the setting of damper 30, enters the opening 29 and passes into and through the combustion chamber. The air in the combustion chamber 35 circulates under and around the fire pot to pass therein through the grates 26 and through the apertures 28. It will be obvious that the air entering through grates 26 will provide the primary air of combustion, while the air passing 40 through apertures 28 will provide a secondary air of combustion by which ignition of heated gaseous products of combustion may be obtained to assure complete combustion and maximum efficiency. The heated air then passes over the 45 oven, around the opposite end thereof, and therebelow, to the flue, as is conventional. The air within the panel 36 which does not enter opening 29, exhausts at the panel top between the end wall and flange 39. The air thus circulates and 50 is directed over substantially the entire inner face of panel 36 to protect the same against the high degree of heat generated within the combustion chamber, to protect the enameled finish thereof. At the same time the panel presents 55 a substantially unbroken appearance to conceal the air passages, damper, etc., and thus enhance the external attractiveness of the range. The simple mounting arrangement permits rapid assembly and facilitates replacement of enameled exterior parts in event of chipping, discoloration, 60 etc. in handling, shipping, or in use. It will be obvious that the panel at the end of the range body opposite the combustion chamber may be of the same construction, and provided with the 65 same type of mounting means as above described, though the air circulation feature may be eliminated if desired.

The panel 17 covering the portion of the range front having the clean out opening is preferably 70 constructed as illustrated in Figs. 6 and 7, and comprises a panel extending flush with doors 16 and 18 by virtue of marginal inturned perpendicular flanges 50. In spaced relation to the ends of panel 17, brackets 51 are secured to the panel 75 at the interior thereof. Brackets 51 preferably

include plate portions 52 parallel to panel 17 and spaced inwardly therefrom a distance less than the width of flanges 50. Plate portions 52 are each provided with a configured cut out having large end portion 53, a reduced intermediate portion having an upper edge 54 below the upper edge of portion 53, and an inner reduced substantially circular locking portion 55 which extends above edge 54. A headed member, such as screw 56, is secured to the front 11 of the range 10 body, with its head spaced therefrom and of a size larger than cut out portion 55, whereby said head may seat behind plate 52 to hold flanges 50 of panel 17 tight against said front. The screws normally pass through portions 55 of the 15 cut outs in plate 52, to operatively position the panel, and the panel 17 is removable to afford access to the clean out opening in front 11 by a combined upward and lateral movement whereby the shanks of the screws pass through reduced 20 intermediate portion of the cut outs to enlarged portions 53 thereof whose size permits passage of the screw heads therethrough for release of the panel therefrom. The adjacent doors 18 normally prevent such separating lateral movement, 25 but may be swung open to accommodate the movement.

It will thus be seen that the normally stationary portions of the exterior panelling of the range are formed of sheet metal panels and provided 30 with simple detachable mountings to facilitate assembly and replacement. At the same time at least some of these panels constitute parts of the air circulating system of the range to afford protective insulation for the panels, to conceal parts 35 of the air circulating system which detract from the appearance of the range when exposed, and to accommodate a novel and effective method of air circulation. With this arrangement is employed a novel fire pot construction which insures 40 supply of adequate air at proper points to insure maximum efficiency of combustion. In this connection, it has been found that when the device is operated, the air which enters the fire pot through the openings 28 above the fuel bed on the grates increases effective combustion as is evidenced by tongues of flame directed inwardly from each opening and constituting combustion of the normal incompletely consumed gaseous 45 products of combustion. Thus a higher heat may 50 be obtained with a given amount of fuel than in conventional range constructions, which promotes economy of operation and minimizes the accumulation of soot and like products of combustion within the range. 55

It will be obvious that in ranges of smaller sizes than here shown, where the warming or reservoir compartment is eliminated, a panel may be mounted on the stove front in place of the warming closet door 18 (at the right in Fig. 1) by 60 the same means as above described for mounting panel 17 or panel 36.

I claim:

1. A range construction comprising a body including a front wall and having a plurality of 65 compartments therein opening at said front wall, a door for each compartment, at least a portion of said front wall being uncovered by said doors, a panel covering said last named wall portion, securing means carried by said wall, and having 70 a head spaced from said wall, and a bracket projecting from the inner face of said panel and having a configured cut-out therein for reception of said securing means with said head seated between said bracket and panel. 75

2. A range construction comprising a body including an apertured front wall and having a plurality of compartments therein accessible through said apertures, a door closing each compartment, said doors covering the major portion of said front wall and projecting outwardly of the plane thereof, a panel adjacent said doors and covering a portion of said wall, said panel lying flush with said doors and having inturned 10 marginal flanges engaging said wall, a bracket carried by the inner face of said panel and including a plate parallel to said panel and spaced therefrom less than the width of said marginal flanges, said plate having a configured cut out 15 therein including a reduced off-set portion, and a member carried by said wall and having a head spaced from said wall, said member normally projecting through the reduced off-set portion of said cut-out with said head seating against said 20 plate to releasably hold said panel with said flanges engaging said wall.
3. A range construction comprising a body including an apertured front wall and having a plurality of compartments therein accessible 25 through said apertures, a door closing each compartment, said doors covering the major portion of said front wall and projecting outwardly thereof, a panel covering a portion of said wall, said panel carrying a bracket at its inner face 30 including a locking portion spaced from said panel, a locking member carried by said wall and interlocking with said locking bracket portion to position said panel flush with said doors, said bracket and member being separable by movement in the plane of said panel, one of said doors being adapted to restrain said movement when closed.
4. A range construction comprising a body having a combustion chamber and an apertured end wall, at least one wall aperture communicating with said chamber, an end panel spaced from and concealing said wall and forming a passage between said wall apertures, and means carried by said body for detachably securing said panel to said wall.
5. A range construction comprising a body hav-
- ing an end wall, a bottom, and a top, a partition in said body extending diagonally between said bottom and end wall, said bottom and end wall having apertures therein respectively outwardly of and below said partition, an end panel having marginal inturned flanges engaging said end wall at the bottom and sides thereof, said panel terminating in spaced relation below said top and spaced from said end wall, whereby air entering through said apertures passes upwardly within 10 said panel and exhausts at the upper end of the panel.
6. A range construction comprising a body having a combustion chamber defined in part by an end wall and a bottom, said end wall having 15 spaced apertures therein, a damper for one of said apertures, said bottom having an aperture, a plate closing said chamber interiorly of the other wall aperture and the bottom aperture, and a panel spaced from and concealing said end 20 wall, said panel having a sealing abutment with said end wall at its sides and bottom and providing an air outlet opening at its top.
7. A range construction comprising a body having a combustion chamber defined in part by 25 an end wall, said wall having an air intake opening communicating with said combustion chamber, a damper for said opening, and a panel fitting over and concealing said wall in spaced relation thereto, said panel having marginal flanges 30 and cooperating with said body to define an air duct between said wall and panel open at the bottom of the range for supplying air to said combustion chamber through said opening.
8. A range construction comprising a body 35 having vertical walls, an outwardly projecting body portion at one vertical corner, a bracket secured to said body at an adjacent vertical corner, a panel having marginal inturned flanges, an ear parallel to said panel carried by one vertical 40 flange, said ear and flange having an opening fitting over said bracket for interlocking said ear and bracket, and means for securing one flange in abutting relation to said body corner projection.

SAMUEL KLUTE.
